Primary Examiner — David Muller*(74) Attorney, Agent, or Firm* — Heslin Rothenberg Farley & Mesiti, P.C.; Victor A. Cardona, Esq.(57) **CLAIM**

The ornamental design for a drip chamber for medical lines, as shown and described.

DESCRIPTION

FIG. 1 is a perspective view of a drip chamber comprising the new design;

FIG. 2 is a top plan view thereof;

FIG. 3 is a bottom plan view thereof;

FIG. 4 is a left side elevation view thereof;

FIG. 5 is right side elevation view thereof;

FIG. 6 is a front elevation view thereof; and,

FIG. 7 is a rear elevation view thereof.

The broken lines shown in the drawings illustrate portions of the drip chamber for medical lines that form no part of the claimed design.
